UNITED STATES PATENT OFFICE.

LLOYD WARREN BAKER, OF BLUE RAPIDS, KANSAS.

RAIL STRAIGHTENER.

Application filed August 20, 1925. Serial No. 51,416.

To all whom it may concern:

Be it known that I, LLOYD WARREN BAKER, a citizen of the United States, and a resident of Blue Rapids, in the county of Marshall and State of Kansas, have invented certain new and useful Improvements in Rail Straighteners, of which the following is a specification.

My invention relates to improvements in rail straighteners or benders and it consists in the combinations, constructions and arrangements herein described and claimed.

An object of the invention is the provision of a simple, reliable and easily operable device which affords facilities for making use of a relatively slight force to bend a rail or a like member which offers a relatively great resistance to a bending stress.

A further object of the invention is the provision of a device of the character described which can be used to bend a short length of rail which is secured at spaced points on ties or other supports without removing the rail from its supports and in such manner as to brace the rail between two adjacent supporting members to which the rail is secured.

Other objects and advantages of the invention will be apparent from the following description, considered in conjunction with the accompanying drawings, in which

Figure 1 is a perspective view of the improved rail bending device applied to a rail, Figure 2 is a horizontal section taken on a plane extending through the rail engaging members of the device, the rail being shown in plan.

Figure 3 is a fragmentary sectional view taken substantially along the line 3—3 of Figure 1.

The body of the improved rail straightening device is of substantially inverted U-shape as shown in Figure 1 and comprises the web portion 1 and a pair of arms 2 and 3 respectively. The end portions of the arms 2 and 3 may be enlarged laterally as indicated at 2^a and 3^a respectively, the lateral enlargements of the respective arms extending at opposite sides of the body of the device.

The respective enlarged end portions 2^a and 3^a of the arms of the body of the device are formed with aligned lateral cut-outs or

recesses 4 and 5 respectively which respectively are open at opposite sides of the body 55 of the device and constitute seats for the reception of spaced portions of a rail 6 or other similar elongated member.

The upper and lower walls of each of these seats 4 and 5 are horizontal and parallel 60 with each other while the inner or back wall of the seat is vertical and at right angles to said upper and lower walls of the seat.

The web portion of the body of the device may be flattened intermediate the ends of the arms of said body as indicated at 7 and this flattened portion has a vertical opening 8 formed therethrough. The wall of the vertical opening 8 has screw threads for engaging with the external screw threads on the shank of an operating rod 9. The operating rod 9 may have an enlarged upper end portion 10 having a plurality of diametrical openings 11 formed therethrough. A handle or cross bar 12 can be projected through any one of the openings 11 in the upper end portion of the operating rod and the ends of this handle or cross bar then may be conveniently grasped and manipulated to turn the operating rod. The peripheral face of

the enlarged upper end portion 10 of the operating rod may be knurled or otherwise roughened as indicated at 13 so that this enlarged upper end portion of the operating rod may be grasped firmly in the hand of an operator and the operating rod turned for a time without the use of the cross bar or handle 12 during each complete operation of the device, as will hereinafter be made apparent.

The lower end portion of the operating rod 9 extends through a vertical opening in the web portion 14 of a puller head which also is substantially of inverted U-shape and comprises a pair of arms 15 which are integral with the web 14. The operating rod can turn freely in the opening in the web 14 but is held against any appreciable axial movement in respect to the web 14 by an upper collar 16 which is secured on the operating rod close to the upper face of the web 14 and a flange 17 which is formed on the lower end portion of the operating rod underneath the web 14 of the puller member. The collar 16 may be pinned to the operating rod and is held against axial movement 100 on the latter.

A pusher head is provided at the lower end of the operating rod. This pusher head may be in the form of an annular member or collar 18 which is disposed on the extreme lower end portion of the operating rod and abuts the flange 17 at its upper end while the lower end of the collar 18 is flush with the lower end of the operating rod and the collar 18 is turnable on the operating rod but is held against displacement from position on the operating rod by reason of the engagement of the upset lower end portion 19 of the operating rod with the slightly enlarged lower end portion 20 of the bore of the collar 18.

The arms 16 of the puller member are twisted slightly so that the lower end portions thereof extend laterally of opposite sides of the vertical plane extending through the web portion 14 of the puller member diametrically of the opening in such web. The arms 15 are provided at their lower ends with inturned lugs 21, each of which is of substantial length.

From the foregoing description of the various parts of the device, the operation thereof may be readily understood. Let it be assumed that a portion of the rail 6 between adjacent ties or like supports is depressed. The arms 3 of the body of the device are placed at opposite sides of the rail and the body of the device then is turned so that portions of the rail at opposite sides of the downwardly bent portion of the rail enter and engage with the seats 4 and 5. The arms 15 of the puller head of the device are disposed at opposite sides of the rail and this puller head is turned about the axis of the operating rod 9 until the lugs 21 are disposed underneath the base flange of the rail. The operating rod 9 then is turned until a pull upward is exerted on the web of the puller head by reason of the engagement of the threaded operating rod or screw with the web portion of the body of the device. It is obvious that the upward pull on the rail will continue so long as the screw 9 is turned in a counter clockwise direction. A relatively slight force thus can be exerted to cause a relatively great upward pull on the downwardly bent or depressed portion of the rail and this pull will be sufficient to straighten the rail without there being any necessity of removing the rail from the ties to which it is secured normally. Should it be desired to bend the rail downward, the screw 9 is turned in a clockwise direction and the pusher head 18 will bear against the upper face of the head of the rail, causing downward flexure of the rail to be effected and continued turning of the screw 9 in a clockwise direction will cause the rail to bend downward as desired. It is obvious that the device can be employed to bend other members as well as

rails and that the device can be turned on its side and utilized to effect bending of a rail or other elongated member in a horizontal plane as well as in a vertical plane.

Obviously, my invention is susceptible of embodiment in forms other than that illustrated herein and I therefore consider as my own all such modifications and adaptations thereof as fairly fall within the scope of the appended claims.

I claim:—

1. A rail-bending device comprising a body of substantially inverted U-shape, the arm portions of said body having lateral seats adjacent to their extremities at opposite sides of the body for the reception of spaced portions of a rail, said body having a threaded opening through the web portion thereof intermediate the ends of said arms, a screw in threaded engagement with the wall of said threaded opening, a puller head of inverted U-shape having an opening in the web portion thereof through which the lower end portion of said screw extends, means on said screw preventing axial movement of the web of the puller head on the screw, the arms of said puller head having inwardly turned lower end portions adapted to extend from opposite sides of the rail underneath the base flange of the rail.

2. A rail bending device comprising a body of substantially inverted U-shape, the arm portions of said body having lateral seats adjacent to their extremities at opposite sides of the body for the reception of spaced portions of a rail, said body having a threaded opening through the web portion thereof intermediate the ends of said arms, a screw in threaded engagement with the wall of said threaded opening, a puller head of inverted U-shape having an opening in the web portion thereof through which the lower end portion of said screw extends, means on said screw preventing axial movement of the web of the puller head on the screw, the arms of said puller head having inwardly turned lower end portions adapted to extend from opposite sides of the rail underneath the base flange of the rail, and a handle engageable with the upper end portion of said screw for turning the screw.

3. A rail bending device comprising a body of substantially inverted U-shape, the arm portions of said body having lateral seats adjacent to their extremities at opposite sides of the body for the reception of spaced portions of a rail, said body having a threaded opening through the web portion thereof intermediate the ends of said arms, a screw in threaded engagement with the wall of said threaded opening, a puller head of inverted U-shape having an opening in the web portion thereof through which the lower end portion of said screw

extends, means on said screw preventing axial movement of the web of the puller head on the screw, the arms of said puller head having inwardly turned lower end 5 portions adapted to extend from opposite sides of the rail underneath the base flange of the rail, the arms of said puller head be-

ing twisted to extend laterally of opposite sides of a vertical plane extending longitudinally of the web of the puller head and 10 diametrically of the opening in the web of the puller head.

LLOYD WARREN BAKER.
